United States Patent

Des. 234,606
Patented Mar. 25, 1975

234,606

ROOM DEODORIZER BODY

William L. Gamble, 1 Waterville Road,
Farmington, Conn. 06032

Filed June 6, 1973, Ser. No. 367,489
(Filed under Rule 47(b) and 35 U.S.C. 118)

Term of patent 14 years

Int. Cl. D23—04

U.S. Cl. D23—150

FIG. 1 is a perspective view from the front and above of a room deodorizer body showing my new design; FIG. 2 is a side elevational view thereof; FIG. 3 is a rear elevational view thereof; FIG. 4 is a front elevational view thereof; FIG. 5 is a top plan view thereof; and FIG. 6 is a bottom plan view thereof.

I claim:

The ornamental design for room deodorizer body, as shown.
